UNITED STATES PATENT OFFICE.

JOHN F. A. DAVIS, OF WENHAM, MASSACHUSETTS, ASSIGNOR TO AMERICAN GLUE COMPANY, OF BOSTON, MASSACHUSETTS, A CORPORATION OF MASSACHUSETTS.

ABRASIVE COVERING FOR SANDERS.

Application filed July 2, 1926. Serial No. 120,207.

The present invention relates to an improved abrasive covering for the wheel of a sanding machine, which wheel is rotated during the operation of the machine for sanding purposes.

The abrasive covering used for this purpose usually consists of a base sheet of paper or other suitable fibrous material more or less flexible, and the abrasive is fixed to it by means of glue, or other binder of suitable character, to form a bond between it and the paper and securely hold in place the abrasive embedded within it.

The abrasive covering is secured to the wheel by wrapping it around the wheel and securing its ends within a slot cut lengthwise in the wheel. This slot is a relatively narrow one and necessitates sharp bends being formed in the covering adjacent its ends to permit their entering the slot. Such bending of the covering has given great trouble by causing either a fracture in the binder which secures the abrasive to the base sheet or paper or a fracture in both the binder and the paper or at least a weakening of the paper at the point or points of the bends. In case the binder only is fractured the tendency is for it during the operation of the wheel to strip from the paper, the stripping beginning at the point of the fracture. In case there is a fracture in both binder and paper or weakening of the paper then there is a tendency for the paper itself to strip from the wheel. Either or both of these difficulties may arise before the usefulness of the abrasive covering has become in any way impaired and accordingly causes great annoyance, to say nothing of loss of time, possibility of injury to the work and loss of the covering.

The object of the invention is to overcome these difficulties, and I have found that they may be overcome by a fixing of the covering before its attachment to the sanding wheel, and this by a fixing, as will later be explained, of the binder portions of the covering which lie adjacent the respective ends thereof and in which portions the bends occur where the ends of the covering are turned to fit within the slot in the sanding wheel on applying the covering thereto.

The invention can best be seen and understood by reference to the drawings in which—

Figure 1 is a side elevation of the improved covering.

Fig. 2 is a plan.

Fig. 3 is an end elevation of the covering curled in position to be applied to the wheel or roll of a sander.

Figs. 4 and 5 are views partly in section and partly in side elevation illustrative diagrammatically of one method of treating the covering for overcoming the difficulties sought to be overcome, in accordance with the object of the invention.

Referring to the drawings:—

1 represents the improved abrasive covering for the sanding wheel. It comprises a base sheet 2 of paper or other suitable fibrous material and an abrasive-carrying adhesive binder 3 bonded at 4 to the surface of the base sheet or paper.

5, 5, represent the inturned ends of the covering which are the ends turned to extend into the slot of the sanding wheel (not shown) and be there retained in the usual manner.

The ends are turned in the general direction of the uncoated side of the covering and as the ends are rather abruptly turned, sharp bends are necessarily formed in the covering adjacent the ends which cause the difficulties previously referred to.

According to the present construction the abrasive-carrying binder 3 in those portions 6, 6 of the covering adjacent its ends is fractured, by minute cracks relatively close together with extension generally crosswise the covering whereby the integrity of the binder along said portions of the covering is destroyed, but the integrity of the base sheet and that of the bond between the sheet and the binder is maintained along those portions. In other words, the binder is so fractured or cracked that when the covering is applied to the sanding wheel and the portions adjacent its ends abruptly bent there will be no localized fracture or cracking of the binder as might cause it to break away from the sheet, or throw stress on the sheet, thereby either breaking or weakening it, inasmuch as the binder has already been so cracked as to prevent this. The cracking of the binder does not destroy the bond between it and the sheet nor does it affect the integrity of the sheet although it tends to give pliability to the sheet and impart a convexity thereto along those portions 6—6 thereof in which the cracks occur.

This effect is obtained by mechanism illustrated in Figs. 4 and 5. A roll 7 of elastic material such as rubber is provided and 110

the roll is rotatable in the direction indicated by the arrow thereon. Arranged adjacent the roll is a plunger 8 having a curved end 9 which engages the roll. The plunger is 5 backed by a strong spring 10 the tension of which when the spring is released throws the plunger in the direction of the roll and causes its curved end to press into the roll substantially as shown in Fig. 5 forming a rounded 10 depression therein. Just beyond the point where the curved end of the plunger meets the roll is a stop 11. The spring-pressed plunger is controlled by any suitable mechanism (not shown) so that the plunger may be 15 released or retracted as occasion requires.

In the operation of the mechanism, with the plunger occupying a retracted position, one end of the abrasive covering is inserted over the curved end 9 of the plunger and between it and the side of the rotating roll until the end of the covering engages the stop 11, the coated side of the paper then facing the roll. On the release of the spring the plunger will force the covering hard against 25 the roll and will effect a bend in the covering as the curved end of the plunger presses into the roll. As the roll is rotating such curving or bending of the covering will continue from the point of the initial application of the 30 plunger to the nearest end of the covering inasmuch as the rotation of the roll will cause the covering to be thrown out from between the roll and the plunger. The effect is that the binder will be fractured by minute cracks 35 relatively close together with extension generally crosswise the covering in those portions which have been thus bent but without injuring the base sheet or paper or destroying the bond between the binder and the paper inasmuch as the paper and the binder are being 40 held hard pressed against the yielding surface of the roll while the binder is being fractured. The fracturing of the binder tends to impart a convexity to the ends of the covering 45 along the portions 6, 6 thereof in which the binder is fractured.

By thus fracturing the binder at the ends of the abrasive covering before its application to the sanding wheel the difficulties are overcome in accordance with the objects of the invention first pointed out, for when the cov-

ering is applied to the wheel no strain will come upon the binder as will cause it to strip from the base sheet or paper, nor will there be any fracturing or weakening of the base 55 sheet, the minute cracking of the binder at the points where the bends occur eliminating all such strain upon the base sheets as might otherwise tend to break it or at least weaken it.

By the term "sanding wheel" as herein used 60 is broadly meant any wheel or drum to which an abrasive covering is applied and the ends secured by fitting within a slot in the wheel or drum.

Having thus fully described my invention, 65 I claim and desire to secure by Letters Patent of the United States:—

1. An abrasive covering for a sanding wheel in which the ends of the covering are attachable to the wheel, comprising a base sheet of 70 fibrous material and an abrasive carrying adhesive binder bonded to the sheet, the binder along those portions of the abrasive covering adjacent to the respective ends thereof and prior to the attachment of the abrasive 75 covering to the wheel being fractured by minute cracks relatively close together with extension generally crosswise the covering whereby the integrity of the binder along said portions of the covering is destroyed but the 80 integrity of the base sheet and that of the bond between the base sheet and binder along said portions of the covering is maintained.

2. An abrasive covering for a sanding wheel in which the ends of the covering are attachable to the wheel, comprising a base sheet of 85 fibrous material and an abrasive carrying adhesive binder bonded to the sheet, the binder along those portions of the abrasive covering adjacent to the respective ends thereof 90 and prior to the attachment of the abrasive covering to the wheel being fractured by minute cracks relatively close together with extension generally crosswise the covering whereby the integrity of the binder along 95 said portions of the covering is destroyed and convexity imparted to said portions of the covering, but the integrity of the base sheet and that of the bond between the sheet and binder along said portions of the covering is 100 maintained.

JOHN F. A. DAVIS.
